UNITED STATES PATENT OFFICE.

JOHN J. BATE, OF BROOKLYN, NEW YORK.

IMPROVEMENT IN REFRIGERATING PROVISION-CARS.

Specification forming part of Letters Patent No. 123,077, dated January 30, 1872; antedated January 15, 1872.

I, JOHN J. BATE, of the city of Brooklyn, in the State of New York, have invented certain Improvements in Refrigerating Provision-Cars, of which the following is a specification:

My invention relates to that class of cars commonly called provision-cars, and which are intended for the conveyance of fresh meats, game, &c., the distance between the point of departure and of delivery being so great as to require the use of some artificial means for the preservation of the meat, &c.

The accompanying drawing represents a car with my improvement forming a part thereof, Figure 1 being a view of the interior of the car, the roof being removed, and Fig. 2 a view by vertical section on the dotted line of Fig. 1.

The means shown by this drawing are designed to keep up a free circulation of air through the provision-chamber *a*, the air being used over and over again, and being forced through an ice-chamber, *b*, well filled with ice, by which the air is cooled, deprived of its moisture, and purified, so that the air circulating through the provision-chamber and the meats, &c., within the chamber, will be kept in a sweet and pure condition. The circulation of air, when the car is in motion, is maintained by a blower or rotary fan, *c*, placed in the messenger's room *d*, or in the ice-chamber. The rotation of the fan is kept up by a band or cord passed around the axle of the car, around a pulley, *e*, and a pulley, *f*, on the shaft of the fan, as is shown by Fig. 1. The air is brought over the partition *g*, between the ice-chamber and the provision-chamber through the space *h*, conducted down through the ice to the entrance *i* of the blower, and passes from the blower for distribution through the perforated pipe *j*. At the lower part of the partition *g* is a hinged door, *k*. This door can be kept closed while the blower is in action, so that the entire air will pass through the space *h*, and down through the ice-chamber to the blower; or it may be opened to a greater or less extent for the passage of air through it, so that the strata of air nearest the bottom of

the provision-chamber will be more fully drawn toward the blower than when the air is drawn through the space *g* only.

When the blower is not in action, the car being at rest, by opening the door *k* there will be a circulation of the air from the provision-chamber through the door-space and space *h*, and through the ice-chamber, thus preventing a stagnation of air in the provision-chamber.

In the drawing, *l* indicates the floor of the car, *m* the roof, and *n* the ends of the car.

This arrangement of means for refrigerating the provision-chamber of cars may be applied to the like chambers of ware or provision-houses, and chambers for keeping meats and provisions generally. When so adapted the fan-blower may be operated by any motive power at hand, or mechanical devices convenient, among which may be included clock-movements. When the last-named means are used I prefer that the movements of the clock be actuated by India-rubber springs, instead of metallic springs or weights.

I am aware that a forced circulation of air in refrigerating provision-cars is not new, the same being set forth in the patents granted to D. E. Somes, in 1867 and 1868; and in a patent granted to W. Bray in 1868; but in neither of their patents is there an arrangement for having a natural circulation of the cooled air when the forced circulation is suspended, as is recited in this specification.

What I claim as my invention is—

The arrangement of the door *k*, in relation to the air-spaces, ice-chamber, and tubes, for allowing the circulation of air when the car is not in motion or the blower in action, as herein recited, in combination with a blower or means for a forced circulation of the air, as described.

This specification signed this 12th day of April 1871.

JOHN J. BATE.
